DUPLICATING STATEMENT FORM FOR
LEDGER CARDS

Benjamin S. Davis, Newport News, Va., assignor
to Newport News Overfold Company, Newport
News, Va., a corporation of Virginia

Application March 21, 1939, Serial No. 263,247

3 Claims. (Cl. 282—27)

My invention relates to improvements in duplicating statement forms for ledger cards.

The object of my invention is to provide a form of this character in which a ledger card may be readily inserted therein and while making an entry on the original a duplicate record is made on the ledger card and one or more records made simultaneously.

Another object of my invention is to provide a form of this character in which the sheets of carbon paper are so secured to the record sheets that they may be simultaneously removed from the duplicate records without the fingers coming into contact therewith.

A further object of my invention is to provide a form in which the record sheets may be readily separated after the ledger cards and the sheets of carbon paper have been removed.

A still further object of my invention is to provide a simple and effective form to accomplish the before stated objects, having certain details of structure and combination of parts hereinafter more fully described.

In the accompanying drawing—

Figure 1 is a plan view of my improved form, showing the original ledger card, sheets of carbon paper and the record sheet broken away.

Figure 2 is a transverse sectional view taken on the line 2—2 of Figure 1.

Figure 3 is a longitudinal sectional view on the line 3—3 of Figure 1.

Figure 4 is a plan view of a modified form, showing means for making two record sheets.

Referring now to the drawing, 1 represents an original sheet which, as shown, is ruled to form preferably a monthly statement sheet and is of an elongated form to provide space for a number of entries thereon. The original sheet is preferably made integral with a record sheet 2 and has a vertical line of scoring 3 dividing the same into original and record sheets of the same size. The sheets are folded on the line of scoring 3, so that the record sheet is directly below the original sheet. The upper end of the original record sheet 1 is provided with a transverse scoring 4, whereby the same may be readily severed from the stub 5, as will be later described.

Cemented, or otherwise secured, to the lower face of the stub 5 of the original sheet 1, and above the scoring 4, is a sheet of carbon paper 6, which is of a length less than the record sheet, as shown in Figure 1 of the drawing. The record sheet 2 is provided at its upper end with a transverse scoring 7 forming the stub 8. Cemented or otherwise secured to the stub 8 is a

sheet of carbon paper 9 of a length less than the record sheet and of the same length as the sheet of carbon paper 6. The several sheets forming the statement pad assume the position shown in Figure 1 of the drawing.

In use it will be seen that, when an entry is to be made on the original sheet, the ledger card 10 is inserted sidewise between the two sheets of carbon paper 6 and 9, the statement pad inserted in a typewriting machine and the proper entries made on the original sheet. By means of the carbon sheets of paper 6 and 9 a record is made on the ledger card 10 and also on the record sheet 2. The tablet statement and the ledger sheets may or may not be left in their assembled position, as shown in Figure 1 of the drawing, but whenever an entry is to be made on the original statement the ledger card should be in the position shown in the drawing.

After all the entries are made on the original statement sheet 1, for instance at the end of a certain period, and the statement is to be sent out, the ledger card is removed and filed for record. In order to separate the original and record sheets it is only necessary to grip the stubs 5 and 8 between the fingers of one hand and the lower ends of the original and record sheets 1 and 2 between the fingers of the other hand. By giving a quick snap the stubs 5 and 8 will be separated from the original and record sheets, carrying with them the two sheets of carbon paper 6 and 9. By this arrangement it will be readily seen that the sheets of carbon paper are removed without coming into contact with the fingers. The original and record sheets are left as a unit and are separated on the line of scoring 3, the original sheet 1 sent to the customer and the record sheet 2 retained as an additional record.

When it is desired to have two record sheets, as shown in the modified form in Figure 4 of the drawing, the original sheet 1 and record sheet 2 are made precisely like that shown in my preferred form. The additional record sheet 11 is free at its side edges and its upper end is scored at 12, forming the stub 13 and secured to the sheet of carbon paper 9 above the stub 8 of the record sheet 2. Secured to the stub 13 of the record sheet 11 is a sheet of carbon paper 14. In this form the ledger card is inserted between the sheets of carbon paper 6 and 14. In use, the operation of the modified form is exactly the same as that of the preferred form and therefore, needs no further description.

Having thus described my invention, what I claim is—

- 5 1. A statement form comprising an original and record sheet secured together at one side and folded upon each other and having scoring for separation and having transverse scoring adjacent their upper ends, a sheet of carbon paper secured to the lower face of the original sheet above the scoring and of a length less than said record sheet, and a sheet of carbon paper secured to the record sheet above the scoring and of a length less than said record sheet, whereby a ledger card may be placed between the two sheets of carbon paper, and an original, a ledger and a record copy may be simultaneously made.
- 10 2. A statement form comprising a sheet divided by scoring and folded on said scoring forming an original sheet and record sheet, and said sheets having a transverse scoring adjacent their upper ends, a sheet of carbon paper secured to the lower face of the original sheet above the scoring and of a length less than the original sheet, a sheet of carbon paper secured to the upper face of the record sheet above the scoring and of a length less than the same, whereby a

ledger card may be inserted between the two sheets of carbon paper and an original, a ledger and a record copy simultaneously made.

- 15 3. A statement form comprising an original and record sheet secured together at one side and folded upon each other and having scoring for separation, said original and record sheets having transverse scoring adjacent their upper ends, a sheet of carbon paper secured to the lower face of the original sheet above the scoring and of a length less than the original sheet, a sheet of carbon paper secured to the upper face of the record sheet above the scoring and of a length less than the record sheet, a second record sheet having free sides and its upper end scored, said portion above the scoring secured to the carbon of the first mentioned record sheet, and a sheet of carbon paper secured to the upper end of the second record sheet above the scoring, whereby a ledger card may be inserted between the sheets of carbon paper of the original and second record sheet, and an original, a ledger and two record copies simultaneously made.

BENJAMIN S. DAVIS.
